HIPPOPOTAMUS PUPPET

Juanita A. Casey and Kathleen L. Johnson, Del City,
Okla. (both of 7055 Lennox, Apt. 5, Van Nuys, Calif.
91405)

Filed Jan. 28, 1975, Ser. No. 544,927

Term of patent 7 years

Int. Cl. D21—01

U.S. Cl. D34—2 R

FIG. 1 is a side view with the head turned slightly to show the side and general facial characteristics of a hippopotamus puppet showing our new design.

FIG. 2 is a view of the other side with the head turned slightly to show the general under-head characteristics of the hippopotamus puppet design of FIG. 1.

We claim:

The ornamental design for a hippopotamus puppet, substantially as shown and described.
